US0D1098921S

(12) **United States Design Patent** (10) **Patent No.:** **US D1,098,921 S**
(45) **Date of Patent:** **** Oct. 21, 2025**

(54) **BOTTLE**

(71) Applicant: **PepsiCo, Inc.**, Purchase, NY (US)

(72) Inventors: **Marco Cimatti**, Sleepy Hollow, NY (US); **Zackary Lee Filbert**, Lancaster, PA (US); **Christopher Andrew Gregory**, New York, NY (US)

(73) Assignee: **PepsiCo, Inc.**, Purchase, NY (US)

(**) Term: **15 Years**

(21) Appl. No.: **29/914,631**

(22) Filed: **Oct. 19, 2023**

(51) **LOC (15) Cl.** 09-01

(52) **U.S. Cl.**

USPC **D9/549**; D9/503

(58) **Field of Classification Search**

USPC D9/500, 503-504, 516, 529-530, 537, D9/549, 575

CPC B65D 1/02; B65D 1/0223

(57) **CLAIM**

The ornamental design for a bottle as shown and described.

DESCRIPTION

FIG. 1 is a top front perspective view of a bottle showing the claimed design;

FIG. 2 is a bottom rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dashed broken lines in the figures show portions of the bottle that form no part of the claimed design.

The dot-dash broken lines in the figures show boundaries that form no part of the claimed design.

1 Claim, 8 Drawing Sheets
